UNITED STATES PATENT OFFICE.

WILLIAM J. ELSOM, OF CORTLAND, NEW YORK, ASSIGNOR TO CORTLAND FORGING COMPANY, OF CORTLAND, NEW YORK, A CORPORATION OF NEW YORK.

VEHICLE-TOP.

1,313,076.

Specification of Letters Patent. Patented Aug. 12, 1919.

Application filed December 5, 1914. Serial No. 875,674.

To all whom it may concern:

Be it known that I, WILLIAM J. ELSOM, a citizen of the United States, and a resident of Cortland, in the county of Cortland and 5 State of New York, have invented a certain new and useful Vehicle-Top, of which the following is a specification.

This invention relates to carriage or vehicle covers or tops, and has for its object a 10 particularly simple and efficient arrangement of the bows and links or levers whereby the movement of the front and intermediate bows is uniform and means for locking one of the bows to the main bow, said locking 15 means being operable by the pivotal movement of the bows. Other objects will appear throughout the specification. The invention consists in the novel combinations and constructions hereinafter set forth and 20 claimed.

In describing this invention, reference is had to the accompanying drawings, in which like character designate corresponding parts in all the views.

25 Figure 1 is a side elevation of an automobile body provided with this top showing the top as unfolded or up, the covering or fabric being shown in section.

Fig. 2 is a similar view showing the 30 position of the bows and the locking means when the top is folded, the covering being removed.

Fig. 3 is an enlarged view of the bows illustrating the operation of the lock.

35 This vehicle or automobile top comprises generally a pivoted main bow, a rear bow, an outrigger supported by the main bow and comprising a pivoted bow, a link connecting the pivoted bow and the main bow, the 40 pivoted bow having a catch projecting therefrom and arranged at an angle thereto, the catch being located at the pivot of said bow, and the main bow being provided with a stud near its pivot with which the catch 45 coacts when the outrigger is collapsed, the catch being movable into and out of engagement with the stud by a pivotal movement of the pivoted outrigger bow.

1 is the main bow which is pivoted at each 50 end at 2 to the body of a vehicle in the usual manner.

4 is the rear bow, 5 is an intermediate rear bow carried by the rear bow 4. 6 is the front bow, 7 the link which is arranged on the 55 side of the top, there being one link on each

side, each link being pivoted at its rear end at 8 to one side of the main bow and at its front side at 9 to the rear end of one side of the front bow 6.

10 is a latch located at the rear end of 60 each side of the front bow 6 and being preferably rigid therewith and arranged at an angle thereto, said latch being here shown as hook shaped and extending in a substantially vertical plane. Said latch extends upwardly when the top is unfolded, and rearwardly and downwardly when the top is collapsed, and is formed with a rearwardly extending slot 11 open at its rear or lower end. 70

12 is a stud projecting laterally from each side of the main bow near the pivot 2 thereof, the stud being placed to enter the slot 11 of the latch 10 when the top is collapsed. 75

The top also includes a brace 14 pivoted at its rear end to the main bow 1 above the link 7 and at its other end to the front bow in front of the pivot 9, this brace being connected to one of the parts it connects, 80 as the main bow 1, by a pin-and-slot 15. The pin-and-slot 15 permits sufficient pivotal movement of the front bow 6 on its pivot 9 relatively to the main bow to engage and disengage the latch 10, and the stud 12. 85

The top also includes an intermediate bow 16 between the main bow and the front bow, the intermediate bow being pivoted at each side at 17 to the brace 14 between the ends thereof, and having an arm 18 projecting 90 beyond its pivot, which arm is connected to the link 7 by a link 19. In order that the top will act most efficiently, there are a link 7, latch 10, stud 12, brace 14 and link 19 on each side thereof. 95

Owing to the manner in which the intermediate bow 16 is mounted, the pivotal motion of the bow 6 is transmitted to the bow 16. The bows 6, 16, links 7 and braces 14 constitute what might be called an outrigger, 100 which outrigger is provided with a catch movable out of interlocking engagement with the main bow 1 during the initial part of the opening movement of the outrigger and into engagement therewith during latter part of the closing movement. 105

When the top is collapsed or down, the catch holds the front and intermediate bows from rattling or movement relatively to the main bow, and also, owing to the pin 110

and slot connection, permits sufficient opening movement of the front and intermediate bows relatively to the main bow to allow any of the fabric that may bulge out to be tucked in between said bows.

What I claim is:—

1. A vehicle top comprising a pivoted main bow, an outrigger comprising a bow, and a link pivoted to the main bow and to the outrigger bow and being connected to the outrigger bow by a stop joint and being movable into position to form an extension of the outrigger bow when the top is up, and foldable into a position alongside of the outrigger bow when the top is down, the main bow and the outrigger bow having means for interlocking near the pivot of the main bow when the outrigger bow and the link are being folded and are nearing their extreme folded position, substantially as and for the purpose set forth.
2. A vehicle top comprising a main bow pivoted at its ends, an outrigger comprising a front bow and a link pivoted to the main bow and to one side of the front bow, a brace pivoted to the main bow above the link and to the front bow in front of the pivot thereof, the brace being connected to one of the parts it connects by a pin-and-slot connection, a hook shaped latch rigid with the front bow and arranged at an angle thereto, and a stud projecting laterally from the main bow near the pivot thereof in position to be engaged by the latch, substantially as and for the purpose set forth.
3. A vehicle top comprising a main bow pivoted at its ends, an outrigger comprising a front bow, a link pivoted to the main bow and to one side of the front bow, and a brace pivoted to the main bow above the link and to the front bow in front of the pivot thereof, the brace being pivoted to the main bow by a pin-and-slot connection, a hook shaped latch rigid with the main bow and arranged at an angle thereto at the pivot of the front bow, and a stud projecting laterally from

the main bow and arranged to enter the hook of the latch, substantially as and for the purpose described.

4. A vehicle top comprising a main bow, a front bow, a link pivoted at one end to one side of the front bow and at its other end to the main bow, a brace pivoted to the main bow above the link and to the front bow in front of the pivot thereof, an intermediate bow pivoted at one side to the brace, means for transmitting the motion of the front bow to the intermediate bow, and a latch carried by the front bow and coacting with means of the main bow for positively locking the front bow to the main bow, the latch being arranged to be operated by the pivotal movement of the front bow, substantially as and for the purpose set forth.

5. A vehicle top comprising a main bow pivoted at its ends, an outrigger comprising a front bow, a link pivoted to each side of the main bow and to each side of the front bow, a brace pivoted to the main bow above the link and to the front bow in front of the pivot thereof, the brace being connected to one of the parts it connects by a pin-and-slot, an intermediate bow pivoted at each side of the brace between the ends thereof, means connecting the rear end of the intermediate bow and the link, a hook shaped catch rigid with the front bow and arranged at an angle thereto, the catch being located at the axis of the front bow and extending in a vertical plane, and a laterally extending stud provided on the main bow in position to interlock with the catch, substantially as and for the purpose described.

In testimony whereof, I have hereunto signed my name in the presence of two attesting witnesses, at Cortland, in the county of Cortland, and State of New York, this 13th day of November, 1914.

WILLIAM J. ELSOM.
